UNITED STATES PATENT OFFICE

131,015

DESIGN FOR A FLAGSTAFF

Edward L. Barrett, La Grange, Ill., assignor to Barrett Engineering Company, Chicago, Ill., a corporation of Illinois

Application May 12, 1941, Serial No. 100,906

Term of patent 3½ years

To all whom it may concern:

Be it known that I, Edward L. Barrett, a citizen of the United States, residing at La Grange, in the county of Cook and State of Illinois, have invented a new, original, and ornamental Design for a Flagstaff, of which the following is a specification, reference being had to the accompanying drawing, forming a part thereof, which is a perspective view of a flagstaff embodying my new design.

I claim:

The ornamental design for a flagstaff, substantially as shown.

EDWARD L. BARRETT.
